UNITED STATES PATENT OFFICE.

MARY SVENDA, OF CHARLEROI, PENNSYLVANIA.

DESIGN FOR A HAT.

52,591.

Specification for Design.

Patented Oct. 15, 1918.

Application filed July 2, 1918. Serial No. 243,075. Term of patent 7 years.

To all whom it may concern:

Be it known that I, MARY SVENDA, a subject of the King of Hungary, residing at Charleroi, in the county of Washington and State of Pennsylvania, have invented a new, original, and ornamental Design for a Hat, of which the following is a specification, reference being had to the accompanying drawing, forming a part thereof.

The figure is a perspective view of the hat, showing my new design.

I claim:—

The ornamental design for a hat, as shown.

MARY SVENDA.
